CLAIM

The ornamental design for a muscle massage gun, as shown and described.

DESCRIPTION

FIG. 1 is a front view of a muscle massage gun showing my new design;

FIG. 2 is a rear view thereof;

FIG. 3 is a left side view thereof;

FIG. 4 is a right side view thereof;

FIG. 5 is a top view thereof; and

FIG. 6 is a bottom view thereof;

FIG. 7 is a perspective view thereof;

FIG. 8 is a bottom perspective view thereof;

FIG. 9 is a perspective view thereof, shown in a condition of use;

FIG. 10 is a perspective view thereof, shown in another condition of use;

FIG. 11 is a perspective view thereof, shown in another condition of use; and,

FIG. 12 is a perspective view thereof, shown in another condition of use.

The broken lines of the massage gun attachments shown in FIGS. 9 through 12 are for the purposes of illustrating environmental structure, which form no part of the claimed design.

1 Claim, 12 Drawing Sheets
